Primary Examiner — Eric Yaary(74) *Attorney, Agent, or Firm* — Patterson Thuente
Pedersen, P.A.(57) **ABSTRACT**

An electronic cigarette has a vaporizer to produce vapor to be delivered to its mouth end. The vaporizer includes a tube having inlet and outlet ends. A porous matrix containing a vaporizable liquid, extends around the tube. Wicking fibers extend through side openings in the tube and are configured to wick the vaporizable liquid from the porous matrix into the tube, and electrical heater coil is powered by a battery to vaporize liquid on the wicking fibers in the tube, so that vapor is supplied along the tube end when the user draws on mouth end. An airflow restrictor is provided to accelerate the flow of air along the tube to the heater coil.

ELECTRONIC CIGARETTE

RELATED APPLICATIONS

The present application is a National Phase entry of PCT Application No. PCT/GB2014/051333, filed Apr. 30, 2014, which claims priority from GB Patent Application No. 1307966.0, filed May 2, 2013, said applications being hereby incorporated by reference herein in their entirety.

TECHNICAL FIELD

Embodiments relate to an electronic cigarette.

SUMMARY

Embodiments of electronic cigarette described herein comprise a generally cylindrical housing with a proximal mouth end and a distal end, and within the housing a vaporizer to produce vapor to be delivered to the mouth end, a battery, and sensor circuitry to detect a user drawing on the mouth end and to connect the battery to power the vaporizer to produce vapor, the vaporizer comprising a tube having inlet and outlet ends and extending longitudinally of the housing, supports at opposite ends of the tube for directing airflow into and out of the tube from the inlet to the outlet, a porous matrix containing a vaporizable liquid extending around the tube, wicking fibers extending through side openings in the tube and configured to wick the vaporisable liquid from the porous matrix into the tube, an electrical heater coil in the tube configured to be powered by the battery to vaporize liquid on the wicking fibers in the tube, so that vapor is supplied along the tube to the outlet end when the user draws thereon, and an airflow restrictor to channel the flow of air along the tube to the heater coil.

The supports for the tube may include a mouth end stopper that is push-fitted into the mouth end of the housing, which includes a mouthpiece spigot onto which the outlet end of the tube is received, and an outlet passageway extending through the spigot to provide an outlet for vapor from the tube.

Also, the supports for the tube may include an annular support member that includes a peripheral surface to engage with the interior of the housing, an inlet spigot on which the inlet end of the tube is mounted, and an inlet passageway extending through the inlet spigot to provide an inlet for air into the tube.

BRIEF DESCRIPTION OF THE DRAWINGS

Embodiments of electronic cigarettes will now be described in more detail by way of example with reference to the accompanying drawings, in which:

FIG. 1 is a schematic perspective view of an electronic cigarette.

FIG. 2 is a longitudinal section through the electronic cigarette shown in FIG. 1.

FIG. 3 is an exploded, partial perspective view of the vaporizer illustrated in FIG. 2.

FIG. 4 is an enlarged portion of the sectional view shown in FIG. 2 in the region of its heater element.

FIG. 5 is a sectional view of an airflow restrictor plug shown in FIG. 2.

FIG. 6 is a sectional view of an airflow restrictor ring.

FIGS. 7A and 7B illustrate different wrappings for the wicking fibers around the vaporizer tube.

2

FIGS. 8A, 8B and 8C illustrate different fanned, spread configurations for the wicking fibers.

FIG. 9 is a sectional view through the arrangement shown in FIG. 8B along the line B-B'.

FIG. 10 is an exploded, partial perspective view of an alternative vaporizer.

DETAILED DESCRIPTION

10 Referring to FIGS. 1 and 2, an electronic cigarette 1 includes a generally cylindrical housing 2 conveniently in the form of a tube of plastics material that extends from a proximal or mouth end 3 to distal end 4. An end cap 5 of translucent plastics material is push-fitted into the distal end 4 and a mouth end stopper 6 is similarly fitted into the mouth end 3. The tube 2 is flexible and given rigidity in part by its internal components, as will be described in more detail hereinafter. The tube in one example is made of polypropylene.

20 As shown in FIG. 2, the end cap 5 includes an air inlet 7 so that when the user draws on the mouth end 3, air is drawn into the housing and as will be described hereinafter, vapor is supplied to the user through the mouth end 3. The housing 2 contains a battery 8, sensor circuitry 9 and a vaporizer 10 that produces a vapor to be supplied to the user.

The vaporizer 10 is illustrated in more detail in FIGS. 3 and 4. The vaporizer 10 includes a tube 11, conveniently made of fiberglass material which extends from an inlet end 12 to outlet end 13. The tube 11 has an outer surface 11a and includes diametrically opposed side openings 14a, 14b through which wicking fibers 15 extend, so as to extend diametrically across the interior of the tube 11 and lie along its outside on surface 11a. In the example shown in FIGS. 3 and 4, the fibers 15 are of a heat resistant material such as 30 fiberglass and extend longitudinally along the outside of the tube 11 towards its outlet end 13, but the fibers 15 could extend towards the inlet end 12. Further configurations for the wicking fibers will be described hereinafter.

An electrical heater coil 16 extends diametrically across 40 the tube 11, with the wicking fibers axially within the coil 16. Electrical leads 17a, 17b supply electrical power to the coil 16 from the battery 8 under the control of the sensor circuitry 9 shown in FIG. 2.

A porous matrix that comprises first and second sheets of 45 fibrous material 18, 19 is loaded with a vaporizable material, for example a nicotine and glycerol solution.

The sheet 18 has a lower surface area and absorbency than the surrounding sheet 19 which can retain a larger volume of the liquid. Typically, the sheet 19 has a larger pore size than 50 the sheet 18. The sheet 18 however facilitates transfer of the liquid to the wicking fibers 15 so that the liquid is wicked along the core of the heater coil 16.

One end of the vaporizer 10 includes an annular support member 20 that has a peripheral surface 21 that engages with 55 the interior surface of the cylindrical housing 2. The annular support member 20 has a generally circular end face 22 extending diametrically across the housing 2 from which an axial inlet spigot 23 extends towards the mouth end 3 and receives the inlet end 12 of tube 11. The overlying ends of 60 the sheets 18, 19 are retained between an annular, depending flange 24 and the inlet spigot 23 at the inlet end of tube 11, and generally fill the space between the interior surface of housing 2 and the tube 11. The annular support member 20 is conveniently flexible and made of silicon for example, so 65 that it can be easily manipulated into housing 2 during manufacture. The sheets 18, 19 are wrapped around the tube 11 and thereby locate the wicking fibers 15 along the length

of the outer surface of the tube 11. Spigot 23 includes a through hole to provide an air inlet passageway 23a into the tube 11.

A mouth end stopper 6 includes a mouthpiece spigot 25 that receives the outlet end 13 of tube 11. The end stopper 6 includes an axial outlet passageway 26 through the spigot to pass vapor to a user through the mouth end 3 of housing 2. Also, the mouth end stopper 6 includes a depending flange 27 so that the stopper 6 can be push-fitted into the mouth end 3 of housing 2. The outlet end 13 of tube 11 may extend slightly beyond the matrix 18, 19. Thus there is a gap between the matrix and the mouth end 3 of the housing 2. Also, the mouthpiece spigot 25 which extends into the tube outlet end 13 is longer than the depending flange 27 that engages with the housing 2 so as to provide a gap between the porous matrix 18, 19 and the end stopper 6. This arrangement prevents or reduces leakage of the liquid held in the sheets 18, 19 through the mouth end 3 of the housing. Thus, the annular support member 20 and the mouth end stopper 6 with their respective spigots 23, 25 cooperate with the tube 11 and the housing 2 to provide a sealed plenum containing the porous sheets 18, 19 so as to retain the nicotine containing liquid in the sheets 18, 19 without significant leakage, and to allow the liquid to wick along wicking fibers 15 to be vaporized on operation of the heater coil 16.

A washer 28, conveniently made of rigid plastics material such as polypropylene, is provided between the vaporizer 10 and battery 8 to provide rigidity to the housing 2 in the region of the annular support member 20. The washer 28 includes an air passageway opening 29 and also openings 30 which receive the electrical leads 17a, 17b. The tubular housing 2 thus is relatively rigid to the touch of the user's fingers in the region of the battery 8 and the washer 28 but is more resilient to the touch in the region containing the vaporizer 10 to provide characteristics of tactility that are similar to those of a conventional tobacco containing cigarette.

An air passageway extends from the inlet openings 7 in the end cap 5 between the sensor circuitry 9 and battery 8 to the air passageway 29 in the washer 28 and thence to the inlet 12 of tube 11.

The sensor circuitry 9 may include a light source in the form of LED 31 which, when operated, is visible through the translucent end cap 5.

When the user draws on the mouth end 3, air is drawn through the air inlet 7 in the direction of arrow A past the battery 8 and into the tube 11. The drawing action reduces the air pressure within the housing 2, which is sensed by the sensor circuitry 9. In response, electrical power from the battery 8 is switched by the sensor circuitry 9 to pass through leads 17a, 17b and energize heater coil 16. As a result, liquid which has been wicked by the wicking fibers 15 from the surrounding porous matrix layers 18, 19 is heated and thereby vaporized so that a stream of nicotine containing vapor is passed through the outlet passageway 26 for the user. Also, in response to the pressure reduction, the sensor circuitry illuminates the LED 31 to mimic the burning of a conventional tobacco containing cigarette.

Also, referring to FIGS. 3 and 4, atomization apertures 32 are formed in the tube 11 so that when the user draws on the mouth end 3, the resulting pressure reduction in tube 11 draws liquid from the surrounding porous matrix layers 18, 19 through the apertures 32 and as a result, the liquid is atomized, thereby producing an atomized stream 33 shown in FIG. 4. In this example, the atomization apertures 32 are provided between the inlet end 12 of tube 11 and the heater

coil 16 so that the atomized droplets 33 then pass the heater 16, which encourages further vaporization of the atomized liquid.

Typically, the atomization apertures 32 are of a diameter between 0.1-0.5 mm. In the example of FIG. 3, the atomization apertures 32 are shown diametrically opposite one another but other configurations are possible, for example a distributed arrangement along the tube 11, which may be spatially uniform or otherwise. Also, one or more of apertures 32 may be provided downstream of the heater coil 16, towards the outlet end of the tube 11.

A flow restrictor 34 is provided to accelerate the airflow that passes the heater coil 16. In the electronic cigarette shown in FIG. 2, the flow restrictor comprises an airflow restrictor plug 35 that is press fitted into an end of the airflow passageway through spigot 23 of the annular support member 20. As shown in more detail in FIG. 5 the airflow restrictor plug 35 includes an axial restrictor bore 36 of a smaller cross sectional area than the tube 11 that channels the air drawn through the inlet end 12 of the tube which can improve the vaporization of liquid from the wicking fibers 15 by the heater coil 16. The resistance to draw is also increased by the presence of the airflow restrictor plug 35, which may improve the consumer experience when drawing on the mouthpiece end 3. In one example, the cross sectional area of the restrictor bore 36 is between 10%-60% of the cross sectional area of the tube 11, to provide the aforesaid advantages, although not all embodiments are specifically restricted to this range.

The flow restrictor 34 can be provided in the airflow at other locations upstream of the heater coil 16, and an example is shown in FIG. 6. In this example, the flow restrictor 34 comprises a restrictor ring 37 that includes a generally cylindrical body 38 that can be slid into the tube 11, with a flow restriction orifice 39 to channel the flow, the orifice 39 having cross sectional area between 10%-60% of the cross sectional area of the tube 11 in some embodiments, to provide the aforesaid advantages.

As previously mentioned, the wicking fibers 15 may be disposed in a number of different configurations along the outer surface 11a of the tube 11. In the example shown in FIG. 7A, the fibers 15 are wrapped in a spiral pattern around the outer surface 11a of the tube 11 towards both its inlet end 12 and outlet end 13. In this example, fibers 15a extending out of side opening 14a are wound in a spiral towards the outlet end 13, and fibers 15b extending out of side opening 14b are wound in a spiral towards the inlet end 12, with the same hand as fibers 15a. However, other winding patterns can be used. For example as shown in FIG. 7B, the fibers 15a, 15b are both wound in a spiral pattern towards the outlet end 13 of the tube 11, with opposite hands.

Other winding patterns can be used such as a serpentine pattern around the outer surface 11a of tube 11. Also the fibers 15a and/or 15b could be divided into bunches and each wound differently around the tube 11, with the same or different winding patterns in the same or different directions along the tube 11, with the same or different hands.

The wrapping of the fibers 15 around the outer surface 11a of the tube improves the operation of the vaporizer 10 by increasing their contact area with the sheet 18.

Also, the wicking fibers may be arranged in a spread configuration as shown schematically in FIG. 8A for example. The fibers 15 diverge from one another from the side openings 14a, 14b into generally fan shaped, spread regions 15a, 15b which lie on the curved outer surface 11a of the tube 11. In the example shown in FIG. 8A, the fan

shaped, spread regions **15a**, **15b** both extend from the side openings **14a**, **14b** towards the outlet end **13** of tube **11**.

Alternative spread wicking fiber configurations are shown in FIGS. 8B and 8C. In FIG. 8B, the fibers **15** emanating from side opening **14a** are split into two bundles **15a'** and **15a''** which diverge from the opening **14a** in opposite directions along the outer surface **11a** of the tube **11**. The fibers **15b** emanating from opening **14b** can be similarly split into two bundles **15b'** and **15b''** which diverge from the opening **14b** in opposite directions along the outer surface **11a** of the tube **11**.

In FIG. 8C, the fibers **15a** emanating from side opening **14a** diverge from the side opening along the outer surface **11a** of the tube **11** towards its outlet end **13**. The fibers **15b** emanating from opening **14b** diverge from the opening **14b** along the outer surface **11a** of the tube **11** toward the inlet end **12**.

It will be appreciated that various permutations of the various wicking fiber spreading arrangements shown in FIGS. 8A, 8B and 8C can be used for the different fiber groupings. In the illustrations of FIGS. 8A, 8B and 8C the spread wicking fibers are all configured so as to be spread symmetrically of the central longitudinal axis of symmetry **A-A'** of the tube **11** but it will be appreciated that asymmetrical wicking fiber configurations can also be used.

The spread configuration of the wicking fibers **15** over the outer surface **11a** of the tube also improves the operation of the vaporizer **10**. Referring to FIG. 9, which shows a transverse section through the tube **11** shown in FIG. 8A, the fibers **15** are shown threaded through the coil **16** and diverging into the generally fan shaped spread regions **15a**, **15b** around the outer surface **11a** of the tube **11**. The outermost or largest circumferential spread of the fan shaped spread wicking fiber region **15a** subtends an angle θ with the central longitudinal axis **A-A'** of the tube **11** and improved wicking occurs when the maximum value of θ is at least 30° , i.e., the angle θ subtended by the widest part of the fan shaped region **15a** $0 \geq 30^\circ$, such as $40^\circ \leq \theta \leq 150^\circ$. The fiber region **15b** is similarly spread in FIG. 6 but a different value of θ could be used falling within the aforesaid range. Also the angle θ can be considered as the azimuth in polar coordinates from the axis **A-A'** such that the azimuth corresponding to the widest part of the fan shaped region falls within the aforesaid range.

A modified arrangement is illustrated in FIG. 10 with an alternative form of side openings to receive the wicking fibers **15**. The coil **16** can be slid into an elongate slot **40** formed in tube **11** which is then closed by means of an overlying cylindrical sheath **41** that is conveniently made of fiberglass material so as to have similar properties to tube **11**, which is slid into place from outlet end **13**. In this example, the wicking fibers **15** extend towards the inlet opening **12** of tube **11** rather than the outlet end **13**, with the advantage that their ends can be sandwiched between the tube **11** and the porous matrix sheet, and held firmly between the tube **11** on spigot **23** and the depending flange **24** of the annular support member **20**.

In another modification, the device shown in FIGS. 1 and 2 may have a two part housing **2** so that the vaporizer **10** is attached to the battery **8** and sensor circuitry **9** by a releasable coupling (not shown) along hatched line **X** shown in FIG. 2.

In order to address various issues and advance the art, the entirety of this disclosure shows by way of illustration various embodiments in which the claims may be practiced and provide for a superior electronic cigarette. The advantages and features of the disclosure are of a representative

sample of embodiments only, and are not exhaustive and/or exclusive. They are presented only to assist in understanding and teach the claimed features. It is to be understood that advantages, embodiments, examples, functions, features, structures, and/or other aspects of the disclosure are not to be considered limitations on the disclosure as defined by the claims or limitations on equivalents to the claims, and that other embodiments may be utilized and modifications may be made without departing from the scope and/or spirit of the disclosure. Various embodiments may suitably comprise, consist of, or consist essentially of, various combinations of the disclosed elements, components, features, parts, steps, means, etc. In addition, the disclosure includes other inventions not presently claimed, but which may be claimed in future.

The invention claimed is:

1. An electronic cigarette comprising a generally cylindrical housing with a proximal mouth end and a distal end, and within the housing:
  - a vaporizer to produce vapor to be delivered to the mouth end;
  - a battery; and
  - sensor circuitry to detect a user drawing on the mouth end and connect the battery to power the vaporizer to produce vapor,
 the vaporizer comprising:
  - a tube having inlet and outlet ends and extending longitudinally of the housing, first and second supports at opposite ends of the tube for directing airflow into and out of the tube from the inlet to the outlet, wherein the first support is located at the inlet end of the tube and the second support is located at the outlet end of the tube,
  - a vaporizable liquid holder containing a vaporizable liquid extending around the tube, wicking fibers extending through side openings in the tube and configured to wick the vaporizable liquid from the vaporizable liquid holder into the tube,
  - an electrical heater coil in the tube configured to be powered by the battery to vaporize liquid on the wicking fibers in the tube, so that vapor is supplied along the tube to the outlet end when the user draws thereon, and
  - an airflow restrictor to channel and accelerate the flow of air along the tube towards a central portion of the heater coil, wherein the airflow restrictor is located in the tube between the first support and the heater coil.
2. An electronic cigarette according to claim 1 wherein the airflow restrictor has a restriction orifice with a cross sectional area of between 10%-60% of the cross sectional area of the tube.
3. An electronic cigarette according to claim 1 wherein the airflow restrictor comprises an airflow restrictor ring located in the tube between the inlet end and the heater coil.
4. An electronic cigarette according to claim 1 wherein the first support comprises an annular support member including a peripheral surface to engage with the interior of the housing, an inlet spigot on which the inlet end of the tube is mounted, and an inlet passageway extending through the inlet spigot to provide an inlet for air into the tube.
5. An electronic cigarette according to claim 4 wherein the airflow restrictor is within the inlet passageway.
6. An electronic cigarette according to claim 5 wherein the airflow restrictor comprises an airflow restrictor plug in the inlet passageway.

7. An electronic cigarette according to claim 4 wherein the annular support member includes a depending peripheral flange such that the vaporizable liquid holder is retained between the spigot and the flange.

8. An electronic cigarette according to claim 7 wherein ends of the wicking fibers are retained sandwiched between the tube and the vaporizable liquid holder between the spigot and the flange.

9. An electronic cigarette according to claim 4 including a washer between the annular support member and the battery.

10. An electronic cigarette according to claim 1 wherein the second support comprises a mouth end stopper that is push-fitted into the mouth end of the housing, the mouth end stopper including a mouthpiece spigot onto which the outlet end of the tube is received, and an outlet passageway extending through the spigot to provide an outlet for vapor from the tube.

11. An electronic cigarette according to claim 10 including a gap between the vaporizable liquid holder and the end stopper.

12. An electronic cigarette according to claim 1 including an air inlet opening at the distal end of the housing.

13. An electronic cigarette according to claim 12 including an air feed passageway between the battery and the housing, extending from the air inlet opening to the inlet end of the tube.

14. An electronic cigarette according to claim 1 wherein the sensor circuitry is disposed between the battery and the distal end of the housing.

15. An electronic cigarette according to claim 1 including a light source powered by the battery under the control of the sensor circuitry to be illuminated in response to the user drawing on the mouth end.

16. An electronic cigarette according to claim 15 wherein the light source is disposed at the distal end of the housing.

17. An electronic cigarette according to claim 1 including an end cap push fitted into the distal end of the housing.

18. An electronic cigarette according to claim 1 wherein the housing comprises a first part containing the battery releasably coupled to a second part containing the vaporizer.

19. An electronic cigarette according to claim 1 wherein the vaporizable liquid holder comprises inner and outer sheets of overlying fibrous material, with outer sheet having a greater pore size than the inner sheet for wicking the liquid to the inner sheet by capillary action.

20. An electronic cigarette according to claim 1 including an atomization aperture in the tube configured to allow liquid to be drawn into the tube from the vaporizable liquid holder so as to be atomized by passage through the aperture when the user draws on the mouth end.
